UNITED STATES PATENT OFFICE.

ARTHUR J. ADAMS, OF CHICAGO, ILLINOIS, ASSIGNOR, BY MESNE ASSIGNMENTS, TO WILLIAM S. FERRIS, OF ELKHART, INDIANA, AND ALEXANDER B. LEITH, OF CHICAGO, ILLINOIS, TRUSTEES.

GO-CART OR PERAMBULATOR.

1,094,045.

Specification of Letters Patent. Patented Apr. 21, 1914.

Application filed March 2, 1910. Serial No. 546,926.

To all whom it may concern:

Be it known that I, ARTHUR J. ADAMS, a citizen of the United States, residing at Chicago, in the county of Cook and State of Illinois, have invented a new and useful Improvement in Go-Carts or Perambulators, of which the following is a specification.

My invention relates particularly to folding perambulators, go-carts or baby carriages; and my primary object is to provide a structure of improved construction and operation, my invention having special relation to improved means whereby the perambulator may be either collapsed or opened 10 in a single operation and securely braced and locked in the extended or uncollapsed position.

My invention is illustrated in its preferred embodiment in the accompanying 20 drawings, in which—

Figure 1 represents a side elevational view of a go-cart or perambulator constructed in accordance with my invention; Fig. 2, a broken sectional view taken as indicated 25 at line 2 of Fig. 1 and disclosing the means for automatically folding and unfolding the wheel-forks, or wheel-supports; Fig. 3, a side elevational view showing the structure in a partially collapsed condition; Fig. 30 4, a broken sectional view taken as indicated at line 4 of Fig. 3; Fig. 5, a plan section taken as indicated at line 5 of Fig. 3; Fig. 6, a broken side elevational view showing the structure still more collapsed than in 35 Fig. 3; Fig. 7, a sectional view taken as indicated at line 7 of Fig. 6 and illustrating, in connection with Fig. 6, the manner in which one pair of the wheel-forks is caused 40 to fold in close relation with the running-gear frame in advance of the other pair of wheel-forks; and Fig. 8, a broken perspective view showing a detail of the link mechanism which connects opposite pairs of wheel-forks.

In the preferred embodiment of the invention, which is that illustrated, A represents a running-gear frame; B, B' pairs of wheels located at opposite sides of the running-gear frame; C, a handle foldably connected with the rear portion of the running-gear frame; D, arms pivotally connected with the handle-bars; D', links pivotally connected with the front ends of the

arms D and with the running-gear frame; E, a U-shaped locking-member having its 55 arms pivotally connected with the links D'; F, a seat, which, in the illustration given, is spring-supported on the running-gear frame; F', a back flexibly connected with the rear portion of the seat and having link 60 and guide connections F' with the arms D; G, a carriage-top (shown in dotted lines) mounted on the arms D; H, an adjustable foot-rest; and I, wheel-fork folding and extending mechanism. 65

The running-gear frame may be of any approved construction. In the form shown, it comprises a U-shaped steel bar whose rearwardly turned arms afford side-bars 1 and whose web affords a front cross-member 2; and cross-bars 3 rigidly connecting the side-bars 1 at the junctions of the wheel-fork brackets. The side-bars 1 are curved upwardly at their front end portions, so that the front cross-member 2 occupies a 70 plane somewhat above the plane of the main portion of the running-gear frame. 75

Secured to the side-bars 1 and the cross-bars 3 are wheel-fork brackets 4 with which are connected by means of pivots 5, the 80 wheel-forks, or wheel-supports, 6. The forks 6 at each side of the structure are connected together by a longitudinal bar 7, so that the pair of wheels at each side of the structure is adapted to fold as a unit beneath the running-gear frame. 85

The handle C comprises handle-bars 8 whose lower ends are connected by pivots 9 with the rear ends of the side-bars 1, and whose upper ends are connected by a cross-round 10. 90

The rear ends of the arms D are connected by pivots 11 with the handle-bars 8 some distance above the pivots 9, and the front ends of the arms D are connected by pivots 95 12 to the upper ends of the links D'. The lower ends of the links D' are rigidly secured to the curved members 13 which are connected by pivots 14 with the side-bars of the running-gear frame at the junction of 100 the front wheel-bracket 4. It will be understood that the handle-bars, arms D and links D' are adapted to fold upon the running-gear frame by a parallel-link movement. The space above the seat is flanked 105 by flexible side-pieces, or flaps, 15 whose

upper edge portions are secured to the front portions of the arms D and whose front edge portions are secured to the links D'. The lower edge portions of the flaps project beneath the seat which they embrace and are connected by a cross-member 16 which is adapted to move freely beneath the seat in the operation of folding the structure.

The locking-member E, as stated, is of U-form, comprising a web, or cross-member, 17 and rearwardly extending arms 18 which are connected by pivots 19 with the lower portions of the links D'. The arms 18 extend through guides 20 applied to the inner surfaces of the front portions of the side-bars 1 of the running-gear frame, and said arms, or bars, 18 are provided at their lower edges with locking-notches 21 which are adapted to engage locking-studs 22 with which the guides 20 are equipped at their lower ends. The upper ends of the guides 20 are equipped with coil-springs and followers beneath which the arms, or bars, 18 pass, said springs being shown in dotted lines and designated 23. The springs tend to force the notches 21 into secure engagement with the locking-studs 22 when the structure is in the position shown in Fig. 1. The cross-member 17 of the locking-device E is disposed normally 30 slightly below the front cross-member 2 of the running-gear frame, so that both members may be grasped by one hand in effecting a release.

The seat F is shown mounted on leaf-springs 24 which have downturned front ends secured by rivets 25 to the intermediate cross-bar 3, as shown in Fig. 4. The back F' is joined, by flexible connection 26, to the rear portion of the seat. The upper portion of the back is equipped with guides 27 which receive the web portion 28 of a U-shaped link whose arms 29 have hooked portions 30 which pivotally engage perforations with which the arms D are provided 45 near the pivots 11. The mechanism F' enables the back to be dropped to a reclining position, and also serves to automatically fold the back forwardly upon the seat in the operation of collapsing the go-cart.

50 The carriage-top G need not be described in detail. It is sufficient to state that it is a collapsible top adapted to pass between the handle-bars.

The foot-support H comprises a U-shaped frame 31 which may consist of a bent rod; and a pouch, or boot, 32. The details need not be fully explained, inasmuch as the foot-rest forms no portion of the present invention. It may be stated, however, that the 60 arms 33 of the foot-rest frame are pivotally connected, by eyes 34, with the intermediate cross-bar 3, as shown in Fig. 4; and a U-shaped brace-member 35 is employed to support the foot-rest in the raised position, when 65 desired. The brace 35 comprises a cross-

member, or web, 36 pivotally joined, by eyes 37, to the cross-bar 17 of the locking-device E; and arms 38 which are slidably connected, at 39, with the arms 33 of the foot-support frame.

The wheel-fork actuating and bracing means I preferably comprises a U-shaped member 40 having a cross-member, or web, 41 and upturned arms 42 which are rigidly connected at their upper end portions by rivets 43, to the links D'; link-mechanism 44 connected with the cross-member 41 of the U-shaped lever 40 and connected with the opposite pairs of wheel-forks; and cams 45 and 46 secured to the intermediate portions of the longitudinal bars 7 which connect the front and rear wheel-forks in pairs, said cams being disposed at the inner sides of the bars 7 and adapted to be engaged by the U-shaped lever 40. It will be noted that the U-shaped lever 40 affords virtually a downward extension of the links D', the arms 42 passing inside the side-bars 1 of the running-gear frame and the web, or cross-bar, 41 being disposed approximately at the plane of the longitudinal connecting members 7 of the wheel-forks when the structure is in the extended position.

The link-mechanism 44, in the form illustrated, comprises a pair of links 47 which have their outer ends pivotally connected or linked to the opposite pairs of wheel-forks and their inner ends joined by a vertical pivot 48; and a longitudinally disposed reach, or link, 49 whose rear end is joined to the pivot 48 and whose front end is joined, by a horizontal pivot 50, to a clip 51 rigidly carried by the intermediate portion of the cross-bar 41. As shown in Fig. 8, each bar 7 projects in the rear of the rear wheel-fork 6 and has secured thereto a right-angular clip 52 whose inwardly projecting arm 53 is connected, by a longitudinal pivot 54, to one arm of an angular link 55, whose other arm is connected, by a vertical pivot 56, to the outer end portion of the corresponding link 47. The extremity of each link 47 projects beyond the pivot 56, as indicated at 57, and bears against the inner surface of an upward projection, or ear, 58 with which the longitudinal flange, or arm, 59 of the clip, or bracket, 52 is provided. It will now be understood that when the links 47 are swung rearwardly in the collapsing operation, as shown in Fig. 5, they swing about the vertical pivots 56, while the short angular links 55 swing about the horizontal pivots 54. The operation, in this respect, is similar to the operation of the construction shown in my Patent No. 913,345, granted February 23, 1909; and the manner in which the link-extensions 57 impinge against the upward extensions 58 of the clips 52 to brace the wheel-forks in an extended position, is similar to the action which occurs in the mechanism 130

shown in the patent mentioned, to Fig. 2 of which patent special reference is made.

The cam 45 comprises a shank 60 secured to the corresponding bar 7, and an arm, or tine, 61 carried by an inwardly offset portion 62, said tine extending substantially parallel with the plane of the bar 7, but pointing forwardly and upwardly, as clearly shown in Fig. 1. The cam 46 comprises a shank 63 secured to the inner side of the corresponding bar 7, and furcations, or tines, 64 and 65, the latter of which is offset inwardly with relation to the former. The fork 61 of the cam 45 is longer than are the forks 64 and 65. The end portions of the cross-member 41 of the U-shaped lever 40 are adapted to engage the cams carried by the opposite pairs of wheel-forks and thereby complete the inward folding of the wheel-forks, one after the other, after the link-mechanism 44 has been flexed and effected the initial inward movement of the wheel-forks during the first portion of the operation of folding the structure. In the final portion of the collapsing operation, the cross-member 41 first engages the fork 61 and causes the wheels B to be folded in advance of the wheel B', and the other end portion of the cross-member 41 then engages the fork 65 and causes the wheels B' to follow the wheels B in the completion of the folding operation. In the reverse operation, one end portion of the cross-member 41 engages the fork 64 and causes the wheels B' to swing outwardly, and the other end portion of the cross-member 41 then engages the bar 7, which is separated from the fork 61 by the space 66, thereby beginning the unfolding operation of the wheels B. After the forks have been swung outwardly approximately to the position shown in Fig. 5, the link-mechanism 44 becomes effective to complete the unfolding operation of the wheels. In this final movement, the U-shaped lever 40 is forced between the front wheel-forks 6, or into engagement with bearings 67 at the front ends of the bars 7, so that the front wheel-forks will be effectively braced with relation to each other, being forced outwardly firmly against the internal shoulders 68 of the wheel-fork brackets 4. When the unfolding operation is complete, the locking-notches 21 of the locking-device E engage the studs 22, and the structure is securely locked in the open position.

The operation may be briefly restated. Assuming the structure to be in the extended position, it may be collapsed by grasping the handle-round 10 with one hand and the front cross-member 2 of the running-gear frame and the web portion 17 of the locking-device E with the other hand, closing the last-named hand to effect release of the locking-device E, and bringing the hands toward each other to collapse the carriage.

In this operation, the handle and running-gear frame swing toward each other and the upper ends of the links D' swing forwardly, while the arms D approach the running-gear frame by parallel movement. As the links D' swing forwardly, the U-shaped lever 40 rigidly attached thereto swings rearwardly, thereby operating through the medium of the reach 49, to flex the links 47 with relation to each other and swing the wheel-forks inwardly on their pivots 5. In the continuation of the collapsing movement, one end of the cross-member 41 engages the fork 61 of the cam 45 and causes the wheels B to move inwardly in advance of the wheels B', the opposite end portion of the cross-member 41 thereafter engaging the fork 65 of the cam 46 and completing the inward folding of the wheels B'. In the reverse operation, one end portion of the cross-member 41 engages the fork 64 of the cam 46 and causes the wheels B' to unfold initially in advance of the wheels B, and thereafter the other end portion of the cross-member 41 engages the bar 7 and causes the initial unfolding movement of the wheels B to occur. In the further forward movement of the cross-member 41, the reach 49 operates to bring the links 47 into alignment with each other and force the pairs of wheel-forks apart, and at the completion of the movement the U-shaped lever, or downward extension, of the links D', is forced or wedged between the front wheel-forks, thereby securely bracing them.

In my above-mentioned Patent No. 913,345, there are shown front and rear pairs of links connecting the opposite pairs of wheel-forks, said links being foldable in pairs. In the present construction, I have replaced the front pair of links with the U-shaped member 40 and provided for automatic actuation of the link-mechanism connecting the opposite pairs of wheel-forks. I desire it understood, however, that any suitable link-mechanism connecting the pairs of wheel-forks may be employed.

The foregoing detailed description has been given for clearness of understanding only, and no undue limitation is to be understood therefrom, but the appended claims are to be construed as broadly as permissible in view of the prior art.

What I regard as new and desire to secure by Letters Patent is—

1. In a folding carriage, the combination of a running-gear frame, a handle pivotally connected with the rear portion thereof, inwardly swinging front and rear wheel-forks connected in pairs with the opposite sides of said running-gear frame, links pivotally connected with each other and joining the pairs of wheel-forks near the rear wheel-forks, said links adapted to swing in a plane substantially parallel with the run-

ning-gear frame, arms pivotally connected with the handle-bars, links pivotally connected with said arms and with the running-gear frame, a U-shaped member secured to said last-named links and extending downwardly through the front portion of the running-gear frame, and a link connected with the cross-member of said U-shaped member and connected at its rear end with 10 said first-named links, for the purpose set forth.

2. In a folding carriage, the combination of a running-gear frame, a handle pivotally connected with the rear portion thereof, inwardly swinging front and rear wheel-forks connected in pairs with the opposite sides of said running-gear frame, cams carried by said wheel-forks and having free front ends, links pivotally connected with 15 each other and joining the pairs of wheel-forks near the rear wheel-forks, arms pivotally connected with the handle-bars, links pivotally connected with the front ends of said arms and pivotally connected with the 20 running-gear frame, said last-named links having downward extensions through the running-gear frame with a cross-member connecting them, and a link connecting said cross member with said first-named links, 25 for the purpose set forth.

3. In a folding carriage, the combination of a running-gear frame, a handle pivotally connected with the rear end thereof and adapted to fold forwardly on the running-gear frame, arms pivotally connected with the handle, links pivotally connected with the front ends of said arms and with the running-gear frame, lever-arms depending from and actuated by said links, wheel-forks 35 connected with the opposite sides of the running-gear frame and adapted to fold inwardly and upwardly beneath the running-gear frame, link mechanism connecting said wheel-forks, and a reach-link connected with said link mechanism and actuated by said lever arms.

4. In a folding carriage, the combination of a running-gear frame, a handle pivotally connected with the rear portion thereof, 50 arms pivotally connected with intermediate portions of the handle-bars, links pivotally connected with said arms and with the running-gear frame, a U-shaped lever secured to said links, wheel-forks connected with the 55 opposite sides of the running-gear frame and adapted to fold inwardly and upwardly beneath the running-gear frame, link mechanism connected with said wheel-forks, and a reach-link connecting said link mechanism to said U-shaped lever.

5. In a folding carriage, the combination of a running-gear frame, a handle foldable with relation thereto, wheel-forks foldable inwardly and upwardly with relation to the 65 running-gear frame, link mechanism con-

necting said wheel-forks, cams carried by said wheel-forks, and actuating means for said link mechanism and cams adapted to be actuated in the operations of folding and unfolding the handle and running-gear frame with relation to each other, said actuating mechanism operative to first flex said link mechanism and then complete the fork-folding operation through the medium of 70 said cams.

6. In a folding carriage, the combination of a running-gear frame, a handle pivotally connected with the rear portion thereof, inwardly swinging front and rear wheel-forks connected in pairs with the opposite sides of 75 said running-gear frame, horizontally swinging links pivotally connected with each other and joining the pairs of wheel-forks near the rear wheel-forks, arms pivotally joined to the handle-bars, links pivotally connected with the front ends of said arms and with the running-gear frame, a lever connected with said last-named links, and a reach-link actuated by said lever and serving to actuate said first-named links. 80

7. In a folding carriage, the combination of a running-gear frame, a handle pivotally connected to the rear portion thereof, a front wheel-fork and a rear wheel-fork pivotally connected with each side of the running-gear frame, a bar connecting the wheel-forks at each side of the carriage in a pair, cams carried by said bars and having free front extremities, arms pivotally connected with the handle-bars, links pivotally connected with said arms and with the running-gear frame, and a U-shaped member secured to said links and extending downwardly through the running-gear frame and adapted to engage with said cams and actuate said 90 wheel-forks. 95

8. In a folding carriage, the combination of a running-gear frame, a handle pivotally connected to the rear portion thereof, a front wheel-fork and a rear wheel-fork pivotally 100 connected with each side of the running-gear frame, a bar connecting the wheel-forks at each side of the carriage in a pair, link mechanism connecting said wheel-forks near the rear pair thereof, cams carried by said 105 bars, arms pivotally connected with the handle bars, links pivotally connected with said arms and with the running-gear frame, a U-shaped member secured to said links and extending downwardly through the running-gear frame and adapted to actuate said wheel-forks through the medium of said 115 cams, and connections between said U-shaped member and said link mechanism. 120

9. In a structure of the character set 125 forth, the combination of a running-gear frame, wheel-forks connected with opposite sides thereof to swing inwardly in pairs, cams carried by said wheel-forks, link mechanism connecting said wheel-forks, and a le- 130

ver adapted to flex said link mechanism and thereafter engage said cams in the folding operation.

10. In a structure of the character set forth, the combination of a running-gear frame, a handle pivotally connected therewith, arms pivotally connected with the handle-bars, links pivotally connected with said arms and with the running-gear frame, 10 said links having downward extensions through the running-gear frame with a cross-member connecting them, wheel-supports pivotally connected with the running-gear frame, link mechanism connecting said 15 wheel-supports, cams carried by the wheel-supports, and connecting means between the cross-member of said downward extensions and said link mechanism.

11. In a structure of the character set

forth, the combination of a running-gear 20 frame, a handle pivotally connected therewith, arms pivotally connected with said handle, links pivotally connected with said arms and with said running-gear frame, 25 downward extensions carried by said links, a cross-member joining said extensions, wheel-forks pivotally connected with the running-gear frame, horizontally-swinging links connecting said wheel-forks, cams carried by said wheel-forks and adapted to be 30 engaged by the cross-member of said extensions, and a link connecting said cross member to said horizontally-swinging links.

ARTHUR J. ADAMS.
